ELECTRICAL CONNECTOR

Ewald Krämer, Dresden, Germany

Application November 26, 1938, Serial No. 242,626
In Germany December 17, 1937

6 Claims. (CL 173—361)

This invention has reference to electrical connectors of the plug-and-socket type.

An object of the invention is to provide a new and improved member (plug or socket) of a connector of this type having relatively movable contact elements (pins or sleeves) such that they will always be easily engageable with the contact elements of the co-acting member without any preliminary hand adjustment but under conditions positively ensuring good electrical contact combined with adequate frictional detention against accidental disengagement.

In accordance with the invention a member of an electric plug-and-socket connector comprises an insulating base, spaced contact elements, means mounting the contact elements in the base for relative rocking movement in parallel planes to and from parallelism, and means resiliently urging the contact elements from parallelism, the mounting means being disposed to enable practically constant spacing of the tips of the contact elements during the relative rocking movement.

The arrangement is such that the contact elements, during their engagement with the fixedly located contact elements of the co-acting member of the connector, automatically assume parallelism under the guidance of said fixedly located elements and also provide good electric contact therewith under the resilient pressure tending always to bias them from parallelism.

The said mounting means for at least one of the contact elements may include a roller turnably mounted in the base with its axis so disposed as to enable the required substantially constant spacing of the tips of the contact elements throughout the permitted turning movement of the roller.

Preferably, however, the mounting means for each of the contact elements includes a roller journaled in the base, the axes of the rollers being in parallel and offset.

Other features of the invention appear from what follows.

By way of example and for the purpose of better explaining the invention, one embodiment thereof as applied to the plug member of an electric plug-and-socket connector is illustrated on the accompanying drawing to which reference will now be made.

Fig. 1 represents a section through the plug, on the broken line I—I of Fig. 2, with the contact pins shown in elevation.

Fig. 2 is a plan, the cover being omitted.

Fig. 3 is a side elevation of one of the springs which coact with the contact pins.

1 denotes the plug body or base of any suitable insulating material, such as synthetic resinous composition, and 2 denotes its cover. The contact pins are designated 3 and 4. They are connected, by screwing or press fitting or the like, to rollers 5 and 6 respectively. These rollers are mounted for turning movement in bearings provided in the base 1 and are retained by the cover 2. As will be seen from Fig. 2, they are mounted with their axes parallel and displaced to opposite sides of the parallel diameter of the base. The pins 3, 4 have extensions 15 and 16 respectively projecting inwardly of the base, and blade springs 17 and 18 bear against these extensions at opposite sides for the purpose of obtaining the desired action, namely, opposite movement of the pins 3, 4 in parallel planes to inclined, non-aligned positions. The pins 3, 4 project through elongated openings 19 and 20 in the cover 2.

The rollers 5, 6 are shown provided with bores 7 and 8 for the reception of the ends 9 and 10 of the cable 11 which is introduced into the base through a bore 12. The ends of the cable are secured in the bores 7 and 8 by grub screws 13 and 14.

When the plug is not engaged with its co-acting socket (not shown) the pins 3, 4 assume oppositely inclined (non-parallel) positions under the action of the springs 17, 18. The inclination may be such that a rocking movement in parallel planes about their roller axes through 10 to 12° is sufficient to bring them into parallelism. When the pins are in the inclined position the distance apart of their tips, along the line a—b in Fig. 2, is substantially the same as the distance apart of the intersections of the pin axes with the roller axes, along the line c—d in Fig. 2, and corresponds to the spacing of the sleeves fixedly located in the co-acting socket. In other words, the projected centres of the pin tips and of the pin bases intercept a circle whose diameter practically corresponds to the spacing of the sleeves in the socket to be engaged.

Therefore, the tips of the pins, which need only have a loose sliding fit in the sleeves, can very easily be entered into the sleeves. As the pins are inserted they rock into parallelism under the guidance of the sleeves since the plug twists or turns slightly until the line c—d becomes coincident with the projection of line a—b, when the pins attain parallelism and are fully inserted in the sleeves. It will be understood that during the

insertion and during the consequent rocking movement of the pins the rollers 5, 6 carrying them turn slightly on their respective axes.

Thus, before, during and after insertion, the 5 tips of the pins are at practically the same distance apart corresponding to the spacing of the sleeves in the socket.

When the pins are inserted in the sleeves of the socket good electrical contact is positively 10 ensured, because the springs 17, 18 constantly tend to displace them from parallelism causing them to make pressure contact with the sleeves even though independently they slide loosely in the latter.

15 Instead of the ends of the cable 12 being connected with the pins 3, 4 as described, they may be secured in recesses provided in the base portion 50, such recesses containing brush contacts or rings 51. The last mentioned mode of 20 securing offers the advantage that fatigue of the cable ends due to the movements of the contact pins is avoided. Moreover, if desired, helical springs may surround the rollers 5, 6 for conducting the current from the ends of the flex 25 to the contact pins 3, 4.

Further, instead of blade springs 17 and 18 for biasing the contact pins 3, 4, other forms of springs, such as helical springs, may be employed.

30 Many other modifications within the invention will be apparent. For example, it will be appreciated that only one of the contact pins may be mounted as described for rocking movement to and from alignment with the other 35 and under conditions enabling practically constant spacing of the pin tips during such movement.

Finally, it will also be apparent that although 40 the invention has been particularly described with reference to the plug member of a plug-and-socket connector, it can equally well be applied to the socket member of such a connector, in which case the contact sleeves would be mounted for relative rocking movement in the 45 manner herein described with reference to the plug pins 3, 4.

I claim:

1. A member of an electric plug-and-socket connector, comprising an insulating base, spaced 50 contact elements, means mounting the contact elements in the base for relative rocking movement in parallel planes to and from parallelism, and resilient means constantly urging the contact elements from parallelism, the mounting means having axes substantially displaced relatively a distance equal to the range of movement of the tips of the contact elements to maintain substantially constant spacing of the tips of the 55

contact elements throughout the relative rocking movement.

2. A member of an electric plug-and-socket connector, comprising an insulating base, spaced contact elements, means mounting the contact elements in the base for relative rocking movement in parallel planes to and from parallelism, the mounting means for at least one of the contact elements including a roller journaled in the base with its axis substantially displaced from the mounting means for the other of the contact elements a distance equal to the range of movement of the tips of the contact elements to maintain substantially constant spacing of the tips of the contact elements throughout the relative 15 rocking movement, and resilient means constantly urging the contact elements from parallelism. 5

3. A member of an electric plug-and-socket connector, comprising an insulating base, spaced 20 contact elements, means mounting the contact elements in the base for relative rocking movement in parallel planes to and from parallelism, and resilient means constantly urging the contact elements from parallelism, the mounting 25 means for the contact elements including rollers journaled in the base with their axes parallel and substantially offset a distance equal to the range of movement of the tips of the contact elements. 30

4. A member of an electric plug-and-socket connector as claimed in claim 2, the said roller mounted contact element extending through the roller to form a two-armed lever having as its pivotal axis that of the roller, and the said resilient means acting on one of said arms. 35

5. A member of an electric plug-and-socket connector as claimed in claim 3, each of the said roller mounted contact elements extending through its roller to form a two-armed lever having as its pivotal axis that of the roller, and the said resilient means acting on one of the arms 40 of each lever. 40

6. An electrical connector plug comprising an insulating base, two rollers turnably mounted in the base with their axes parallel and offset, contact pins projecting radially from the rollers beyond the base in two parallel planes normal to the roller axes, extensions on the pins projecting radially from the rollers within the base, and resilient means within the base bearing on the extensions to rock the pins to oppositely inclined 45 positions in said parallel planes, the offset distance of said parallel roller axes being substantially equal to the range of movement of the outer 50 tips of said contact pins. 55
